UNITED STATES PATENT OFFICE

CHRISTOPHER CHARLES DARGIS, OF ATLANTIC CITY, NEW JERSEY

COMBINATION BOX FOR ELECTRO-PNEUMATIC PIPE ORGANS

Application filed June 1, 1931. Serial No. 541,483.

This invention relates to improvements in electro-pneumatic pipe organs, and more particularly to that part of the instrument known to those familiar with the art as the

5 combination box. As the name implies it is the purpose of this box to establish prior to the playing of a selection of music, all of the various combinations that are to be used during the rendition of the said selection, the combination box being operatively connected to the organ mechanism by other associated electrical and pneumatic devices. Through the medium of these devices the combinations are not only established, but 10 at the proper moment during the rendition of the selection the combination may be changed automatically and quickly without any perceptible interruption in the music, merely by the touching of a switch element 15 by the organist, the said switch element being conveniently mounted on the console adjacent or in close proximity to the playing keys.

In the present instance the invention resides in the detail construction of a combination box, and also in the combination of the said box with its coordinating and associate operating devices shown in the drawings and to be hereinafter described.

20 Heretofore combination boxes have been of a very complicated nature, necessitating difficult and awkward constructions for the successful operation of the same. In many cases instruction for operating them have been so confusing even to persons of average skill as to cause them to lose their utility. Still further, because of the multiplicity of intricate mechanisms used in their operation, the cost of building the boxes has been such 25 as to warrant their disapproval.

One object of the invention is to provide a combination box that is comparatively simple in construction yet efficient in operation and possessing the very desirable feature of 30 compactibility in its novel construction as well as low cost of construction.

Another object of the invention is to provide a combination box with associated operating devices which may be operated by, or 35 derive their source of operation from mech-

anisms and means of power supply (both electrical and pneumatic) usually found in the manufacture of the ordinary pipe organ.

Still another object of the invention is to 55 provide an electrical main control or transfer switch which through the medium of a pneumatic action, which is in turn controlled by a master switch button located on the console, causes the initial selection of combination switches to be set or made in the combination box, and also said switch when operated to another position by said pneumatic causes the combination selections originally recorded to be successively made by 60 means of electrical connections from the combination box to the said combination switches through the transfer switch.

A further object of the invention is to 65 provide a system of control, simple in operation and adapted to be mounted adjacent the keys on the keyboard, so that by merely extending a finger the organist may, during the rendition of a musical number, change the combination without any perceptible 70 pause in the playing.

With the foregoing and other objects in view, the invention will be more fully described hereinafter and will be more particularly pointed out in the claims appended 75 hereto.

It is to be understood that the particulars herein given are in no way limitative, and that while still keeping within the scope of the invention, any desired modification of details and proportions may be made in the construction of the appliance according to 80 circumstances.

In the drawings:—

Figure 1 illustrates an organ console of 85 modern type, showing the relation of the combination keys or switches to the playing keys. Also, the relative position of the control panel with its various operating buttons clearly demonstrate the ease with 90 which it may be operated by the organist.

Figure 2 is a plan view of the combination box comprising the invention.

Figure 3 is a front elevation of the said 95 box.

Figure 4 is a sectional elevational view on the line 4—4 of Figure 2.

Figure 5 is a transverse sectional view on the line 5—5 of Figure 3.

5 Figure 6 is an end elevational view of the combination box.

Figure 7 is a diagrammatic electrical wiring diagram illustrating the combination box in relation to its associated operating parts, and showing how the various circuits controlled from the console serve to actuate the said parts, and also including enlarged 10 detached fragmentary longitudinal sectional view through the combination box 15 as a part of Figure 7 more clearly setting forth the circuits of the said combination box as formed by its operating parts.

Figure 8 is a detached fragmentary front elevation view of the transfer switch shown 20 in Figure 7.

Figure 9 is an enlarged elevational view of one of the combination keys or switch elements shown on the console in Figure 1.

Referring more particularly to Figure 1 25 of the drawings 1 designates the console of a modern electro-pneumatic pipe organ. In the present instance three rows of playing keys 2 are shown which are controlled in the usual manner through combination 30 switches 3, the operating pallets 4 of the switches extending through the back 5 of the console. As these combination switches are not new in the art and form no part of the present invention the description of the 35 same will not include the operation of the keys by them but will be confined to structural details of the switch as are affected by the various operating elements of the invention.

40 For the purpose of illustration the control panel 6 is shown mounted on the back 5 of the console and immediately above the top row of playing keys being readily accessible to the finger tips. In actual practice a similar control panel might be mounted on each of the vertical back portions 7 of the keyboard, and affording the organist an opportunity to change the combination conveniently regardless of which keyboard 45 the organist is using at the time of change. As will be obvious, in an arrangement of this type the control panel in one key section will be a duplicate of a control panel in each of the other sections, and switches 50 on one panel will be in parallel circuit with corresponding switches in each of the other panels.

The operation of these switches will be disclosed in detail later in the specification.

60 Located within the housing of the organ proper and suitably supported therein is a combination box 8, comprising in the present instance front and back vertical wall members 9 and 10, and end members 11 and 12 respectively. These members together

with crosstie pieces 13—13 form the main frame of the box and are preferably made of some non-current conducting material such as wood or fibre.

Extending longitudinally of the box proper and yieldably supported against the under side of the end portions 11 and 12 by spring elements 14, are bars 15 also of insulating material. These bars are retained in spaced relation to each other transversely, and are adapted to be moved vertically upon the guide pins 16—16.

70 Suitably retained in the bars 15 are resilient wire contacting elements 17, which extend upwardly between pairs of transversely extending contact wires 18 and 19, the said wires 18 and 19 being securely fastened in the main frame members 9 and 10 of the combination box.

75 The spring contacting elements 17 normally bear against the contact wires 18 and are retained in this position by other transversely extending insulated rods 20. These rods are likewise secured in the frame members 9 and 10 and each rod 20 is positioned 80 immediately above each pair of contact wires 18 and 19.

85 Insulating retaining strips 21 extending longitudinally of the box and secured to the end members 11 and 12 thereof, serve to insulate the resilient contacting elements 17 of adjacent bars 15, and due to a slight flexure of the elements 17 against the strips 21 provided during the assembly of the unit, the elements 17 are held in substantial alignment to each other between their respective contacting wires 18 and 19.

90 Also extending transversely of the combination box 8 and pivotally supported in the members 9 and 10 thereof, are levers 22, having bifurcated elements 23 loosely and pivotally attached to the levers 22 by a rivet or other suitable means at 24. One projecting finger 25 of the elements 23, by reason of gravity normally rests and is supported on the top edge of a bar 26, which extends longitudinally of the combination box 8 and is slidably mounted, at each end of the box in supporting brackets 27 and 28. These brackets have rectangular openings 105 110 115 120 125 130 135 140 145 150 155 160 165 170 175 180 185 190 195 200 205 210 215 220 225 230 235 240 245 250 255 260 265 270 275 280 285 290 295 300 through the rod 34 operatively connected at 35 to the bar 26, bears the bar 26 against the bracket 28, the reduced end of bar 26 providing abutment shoulders 36-36.

5 Extending longitudinally of the box and mounted on the face thereof between the brackets 27 and 28 is a shelf 37. This shelf carries on its top side and securely fastened thereto a plurality of electro-magnets 38 in spaced relation to each other each positioned immediately above a finger 25 of the bifurcated elements 23. The core of each of the magnets extends through the shelf, which is of insulating material, and has suitably fastened to its lower ends a contacting plate 39. These magnets when energized are adapted to magnetize the plates 39, thereby attracting the fingers 25 of the bifurcated elements 23 and causing them to pivot at 24 upon the levers 22 and to be held in contact with the plates 39 as shown in dot and dash lines in Figure 5. This brings the lower fingers 33 into operative engagement with the notches 32 on the bar 26, and it will be obvious then that any movement of the bar 26 will cause the various levers 22 that have been selected by energizing their respective magnets 38, to be turned about their respective pivot points in the frame at 40 and 41. 30 A crank portion 42 of the lever 22 will be then brought to bear against the resilient contact wires 17.

Also extending longitudinally and retained within the side walls 11 and 12 of the box are other levers 43 pivotally mounted therein at 44 and 45. A crank portion 46 adapted to engage the bars 15 and to contact against the wires 17 is provided, while an outer extending crank portion 47 which 40 serves to operate the said levers is pivotally connected at 48 to other levers 49. The levers 43 are retained in normal position by the action of springs 50 which are tensioned between the end wall of the box at 51 and the crank portion 47 at 52. The springs causing the crank portions 46 to abut against a shoulder 53 provided on the end wall 11 of the box.

The levers 49 which are used to actuate the contact levers 43 and are attached at 48 to them, are pivotally secured by pins 54 to the collars 55 and said collars being loosely retained on the reduced end of the levers 43 by cotter pins or the like. Retaining the levers 49 in a substantially vertical position at all times is a bracket 56 mounted on the side wall 12 of the box, having cut-out portions 57 which receive the upper ends of the said levers 49. These cut-out portions 57 are necessarily wider than the width of the lever so as not to interfere with any of its movements. The lower ends of the levers 49 are provided with extending hook portions 58 which are adapted to be engaged by 60 a bracket 59 located on the bellows 114 of the

pneumatic 107, the said bracket being secured to the expanding wing of the bellows.

Normally the hook ends of the levers 49 lie out of the path of engagment by the bracket 59 by reason of gravity. Mounted 70 on the stationary wing of the bellows of the pneumatic in a suitably insulated support 61 are the electro-magnets 62. As in the case of the magnets 38 the cores of the magnets 62 extend through the support 61, and 75 are secured to contact plates 63 on the face of the said support 61. The magnets 62 are equal in number to the levers 49 and when energized they magnetize the plates 63 thereby attracting the particular lever 49 which 80 it controls and drawing it into operative engagement with the bracket 59.

Extending transversely of the box and securely fastened to the underside of the wall members 9 and 10 thereof, is a conductor 64. 85 As will be obvious by referring to Figure 4, resilient spring current distributors 65 securely attached to the conductor 64 extend upward through slots 66 in the bars 15, and bear slightly against the insulating strips 21, thereby supporting the upper ends of the distributors and retaining them in substantial alignment with the contact wires 17.

Referring more particularly to the wiring diagram shown in Figure 7 and to its associate Figures 8 and 9, a more comprehensive understanding of the operation of the combination box together with its associated operating parts may be obtained.

The combination switch 3 as shown in the 100 diagram is of the usual construction. As previously stated the wiring diagram does not include the wiring connections between the switches and the playing keys as this forms no part of the present invention.

Also while there are many such switches used in the installation of a modern pipe organ, the diagram, for the purpose of clarity, shows one of them, and illustrates with accompanying figures clearly how it operates and is in turn operated by the combination box. It will be obvious that if one can control and be controlled, that utilizing the same mechanism any number of switches may be employed.

The switches are mounted on the console in the usual manner as shown in Figure 1, and have within the organ proper a pair of parallel supporting bars 67 between which they are held in position. While forming a 120 support for the switches the bars also act as conductors, being connected by a lead wire 68 to a trunk 69 of one side of a source of current supply.

With reference to Figure 9 the detail construction of one of the switches is shown, illustrating clearly how the various current impulses effect its operation.

The switch proper is encased in a rectangular housing 70 comprising a front por-

tion 71. The pallets 4 which provide a means for operating the switch manually, are fastened to a central switch arm 72 by screws or other suitable means, the said switch arm extending through a slot 73 in the front portion 71 of the housing and pivotally secured by a pin 74 thereto. An arcuately curved end portion 75 radial to the pin 74 is adapted to be moved between a pair of felt stops 76 and 77 suitably retained in metallic cups secured to the housing 70. Extending through a slot 78 in the rear of the housing and yieldably engaging a V slot 79 cut in the end portion 75 of the switch arm 72, is a switch tensioning device 80, adapted to retain the switch arm in either of its two positions. Suitable electromagnets 81 and 82 secured to the front portion 71 of the housing 70 are employed to 20 actuate the switch arm automatically from the combination box. In the position illustrated the switch is in its "off" position. By energizing the coil 81 through the insulated terminal 82 and associated lead wire, 25 the switch arm will be attracted by the magnetized core of the coil 81 sufficiently to overcome the resistance of the tensioning device 80, and "flip" over as it were to the "on" position where it will be retained by the said tensioning device. To bring the switch arm back to its original position the coil 82 is similarly energized through its respective terminal 83 and associated lead wire. In each case the felt stops 76 and 35 77 limit the movement of the switch arm against the tension device 80.

It will be noted that when the switch arm 72 is actuated by the magnet 81, the member 84 of the tensioning device 80 extending 40 through the slot 78 in the housing 70 will be brought to bear against a resilient contact element 85 secured to the insulated terminal 86. In this manner a circuit is completed from the conductor bars 67 through the 45 frame 70 and working elements of the switch itself to the terminal 86.

Associated with the combination box in the wiring diagram is an electrical control or transfer switch 87. This switch comprises a base panel 88 secured in any suitable place within the organ mechanism, having vertically extending bearings 89 at opposite ends thereof, and supporting therein a shaft 90 which has securely fastened to one end an operating lever 91. Rigidly secured to the shaft 90 between the two bearings 89 is a contacting panel 92 which carries on its face two rows of terminals 93 and 94. The terminals 93 connect to flat 55 spring contact elements 95 which extend through the panel 92 to the opposite side thereof, where they index with similarly opposed contact plates 96 mounted on the base panel 88.

The terminals 94 are arranged in pairs

97 and 98 respectively, each pair being disposed immediately above a terminal 93, there being twice as many terminals 94 as there are terminals 93. (Figure 8.) For a reason hereinafter disclosed connected to 70 the terminals 97 and 98 are similar flat spring contact elements 99 and 100 which extend through the panel 92 to the opposite side thereof where they index with similarly opposed contact plates 101 and 102 secured to the base panel 88. The contacting panel 92 is adapted to alternately connect the terminals 93 with the contact plates 96 and the terminals 97 and 98 with their respective contact plates 101 and 102. The motion 80 for actuating this switch panel is derived from the bellows 114 of the pneumatic 106, the said bellows being operatively connected to the lever 91, of the transfer switch 85 through a connecting rod 103.

In the diagram, 105 designates the pneumatic unit that actuates the bar 26 of the combination box 8 through the connecting rod 34. The pneumatic unit for operating the transfer switch 87 is designated at 106. 90 107 identifies the pneumatic unit for actuating the levers 49 and at 108 is shown an auxiliary pneumatic unit used to limit at certain times the downward movement of the bellows 114a of the pneumatic unit 107. 95

Each pneumatic unit comprises a wind box 104 common to every pneumatic organ, a valve 109 operatively controlled by a diaphragm 110; an electromagnetic valve 11; an inter-connecting port 112 between the valve 11 and diaphragm 110; an inter-connecting port 113 between the wind box 104, the atmosphere, and the associated bellows. Each bellows has a spring 115 which normally acts to expel the air from the bellows and to retain the bellows in a collapsed condition. 105

On the control panel 6 located on the console of the organ are the various push-buttons used in conjunction with the invention. 116 designates a master control button, and 117 designates the six buttons that control six different combinations. It will be understood that the number of combination settings on an instrument of this character can vary. In the drawings the various parts illustrated provide for a possible setting of six combinations although it will be understood that the invention is not limited to six, but a combination box constructed in accordance with the principles involved 115 in the invention can accommodate any number of combinations and likewise any number of combination switches. 120

As has been previously set forth, all combinations that are to be used in the rendition of a musical selection are set previous to its playing. Still referring to Figure 7 let it be assumed that a series of combinations are to be set. 125

The organist after studying the music for 130

- the first combination, will, by depressing the various pallets 4 of the combination switches selected, have caused those certain selections to be transferred to the combination box.
- 5 The switch 3 designated in Figure 7 is shown as having been selected, the pallet 4 having been depressed from the dot and dash position indicated in the drawing. The said switch 3 as before described, being connected to one side of the circuit through the bars 67, completes the circuit through its respective operating parts to the terminal 86 on the housing 70 thereof. From this terminal a lead wire 118 continues the circuit to a terminal 93 on the transfer switch 87.
- In each instance where a combination switch is manually selected a similar circuit is closed between the respective combination switch and the control or transfer switch 87.
- 20 The various combination keys or switches being selected, must now be set within the combination box, so that at the proper point in the rendition of the musical selection this original setting will, through the control transfer switch 87 and other associated mechanism shown, restore the switches to their original setting.
- This is accomplished by depressing the first push-button 117 of the group shown on the control panel 6. The first button is indicative of the first combination, the second button of the second combination, and so forth.
- 35 By depressing the button 117 three circuits are closed and simultaneously three actions result.
- First, current from a trunk conductor 122, said conductor connecting to one side of a source of power 123, passes through the lead wire 124 and energized the electro-magnetic valve 111 of the pneumatic unit 106, the other side of the circuit being constant through the line 125 which connects it to a trunk conductor 69.
- 40 Normally the air pressure in the wind box 104 of the pneumatic unit 106, exerted against the greater surface area of the diaphragm 110 thereof, seats the valve 109 against the inner face of the port 113, allowing the bellows 114 to communicate with the atmosphere. This results in the deflation of the operating bellows 114 through its associated spring 115.
- 50 The valve disc of the electro-magnetic valve 111 also normally seats under air pressure of the wind box 104, and closes the communicating port 112 to the said pressure.
- 55 However, immediately upon the energization of the magnet of the electro-magnetic valve 111, by depressing the push button 117, the metallic valve piece of the valve 111 is raised, and air pressure enters the port 112 causing the diaphragm 110 to expand and seat the valve 109 against the outer face of the port 113. This closes the said port 113 to atmosphere, and allows the air pressure to enter the bellows, expanding the same against the action of the spring 115.
- 60 Through connecting rod 103 and lever 91 the panel 92 of the switch 87 is caused to pivot about the shaft 90 in a counter clock wise direction, bringing the flat spring contact elements 95 of the terminals 93 into contacting engagement with the opposed contact plates 96 on the base 88 thereof, causing the circuit from the combination switch 3 to be closed through the transfer switch 87, through the lead wire 119 to the magnet 38 on the combination box 8. A lead wire 120 connecting the magnet with the opposite side of the circuit completes the said circuit through the trunk conductor 122.
- 65 This causes the magnet 38 to be energized which in turn causes the bifurcated member 23 of the lever 22 to pivot at 24, thereby bringing the finger 33 into operative engagement with the notch 32 on the bar 26, as shown at 121 in Figure 7 and in dot and dash lines in Figure 5.
- In this manner all of the combination switches selected on the console, magnetize their corresponding magnetic cooperating parts on the combination box 8, through the medium of the transfer switch 87.
- 70 The second circuit to be closed through the depression of the button 117 is described as follows.
- 75 The current from the said trunk conductor 122 upon depressing the push button 117 is also conducted through a line 126 to one side of a magnet 62, the said magnet 62 being one of a group of similar magnets (not shown) mounted on the stationary wing of the bellows 114a of the pneumatic unit 107. These magnets correspond in number to the operating levers 49, each magnet being an associated part thereof, opposed to, and adapted to magnetically attract the said levers 49.
- 80 The magnet 62 is connected to the other side of the circuit through the line 127, and thence through the trunk conductor 69.
- 85 Current through the line 126 energizing the magnet 62, attracts the lever 49, causing it to pivot on the pin 48 and move its hooked end 58 into the downward path of the bracket 57 secured to the underside of the bellows 114a of the pneumatic unit 104.
- 90 As one lever 49 is controlled, and incidentally the first in line of the group 128 shown on the side of the combination box 8 in Figure 6, it will be understood that each of the levers 49 in the said group may be actuated in a similar manner through their individual circuits 129 shown in Figure 7, operatively controlled through their respective combination push buttons 117. Each of the push buttons 117 representing the control of one setting or combination.

The third circuit to be closed by depressing the said combination button follows.

The current from the trunk conductor 122 is passed through a line 130, and energizes 5 the electro-magnetic valve 111 of the pneumatic unit 107, the other side of the circuit being constant through the line 131 which connects it to the trunk conductor 69. Upon the energization of the magnet of the said 10 valve 111, the associated metallic valve disc of the valve is raised, and air pressure present in the windbox 104 of the unit is allowed to enter the port 112 thereof, balancing pressure on the diaphragm 110 and the pressure 15 to seat the valve 109 against the outer face of the port 113. This closes the said port 113 to atmosphere, and allows the air pressure to enter the bellows, expanding the same against the action of the spring 115. The 20 movable wing of the bellows 114a carrying the bracket 57 operatively engages the hook portion 58 of lever 49 and causes it to be drawn downward as the bellows is inflated.

Referring now to Figures 4 to 6 inclusive, 25 it will be obvious that the downward movement of the lever 49, pivoting on the crank portion 47 of the shaft 43, will cause the said shaft 43 to turn in a clockwise direction in its bearings 44 and 45 against the action 30 of the spring 50. The crank portion 46 of the lever 43 intermediate the ends 11 and 12 of the box, will then bear against the resilient contact elements 17 of the bar 15, but flexing the said contact elements slightly as it 35 passes through its arc generated radially to the pivots 44 and 45, the said crank portion 46 will continuing in its downward path, engage the top of the bar 15 and cause the said bar to be depressed downwardly on its guides 40 16-16 against the action of the springs 14.

This movement in the combination box occasioned by the bellows 114a of the pneumatic unit 107 through the lever 49, results 45 in the lowering of the contact elements 17 on the bar 15, from a position where the tops of the said contact elements are in substantially the same horizontal plane as the top edges of the transversely extending insulated rods 20, to a position slightly lower 50 than the plane of the lower edges of the said rods 20. However, operative contacting relation between the elements 17 and the conductors 18 is still maintained.

Therefore, immediately upon the depression 55 of the push button 117, all of the various combination switches 3 that are selected at the console by operating the pallets 4 thereof, are caused to be selected in the combination box, through their representative corresponding parts in the said box.

The next step is to set the thusly selected combination of keys or switches in the combination box.

This is accomplished by still retaining the 60 push button 117 in its depressed position and

depressing the master switch or button 116. Immediately a lead 132 is connected through the switch 116 with the trunk conductor 122, thereby energizing the electro-magnetic valve 111 of the pneumatic unit 105, the other side 70 of the circuit being constant through the line 133 which connects to the trunk conductor 69. Upon the energization of the valve 111 air pressure enters the bellows, expanding the same, and through the connecting rod 75 34, actuates the notched bar 26, against the action of the spring 115.

Immediately the various levers 22 of the combination box, whose bifurcated end portions 23 and associated fingers 33 thereof, are being held in operative engagement with their corresponding notches 32 on the bar 26, under the influence of the associated magnets 38, are turned in their pivots 40 and 41 of the box in a clock-wise direction. The various 80 bifurcated portions 23 of the levers 22 that have not been selected or magnetized by the magnets 38 will continue to be supported upon the top edge of the bar 26, by the fingers 25 as the bar is advanced forward.

The various levers 22 that are caused to pivot by this movement of the bar 26, bring their respective crank portions 42 to bear transversely against the resilient contact elements 17 of the bars 15. And the contact elements 17 having been lowered to a position clearing the rods 20, are deflected by the levers 22 until the ends of the said elements are substantially the opposite side of the rods 20, causing the central body portion of the 100 elements 17 to impinge against the conductors 19.

As the contact elements on each bar 15 are acted upon, the contact elements in each idle section, on bars 15, will be caused to flex 105 between the rods 20 and conductors 19, but maintaining their original setting. In this manner all of the subsequent settings are preserved, and only changed when the setting is reset through the action of the levers 110 43 and associated operating parts.

After having depressed the master button or switch 116 the combination button 117 is released and a moment later the master button 116. This action breaks the circuits 115 to the various pneumatic units 105, 106 and 107 respectively causing the bellows of each of the units to collapse.

The action of the pneumatic units in each of the cases is the same.

The electro-magnetic valve 111 being demagnetized allows its metallic disc to seat on the valve port opening 112. The air pressure in the wind box 104 exerted against the greater area of the diaphragm 110, causes it to seat the valve 109 against the inner face of the port 113, communicating the bellows 114 with the atmosphere. The bellows under the action of the spring 115 then 125 130 collapse.

The collapsing of the bellows of the unit 107 through the action of the spring 115 and coordinating action of the spring 50 releases the lever 49 and returns it to its normal position, restoring the lever 43 to its normal position, against the stop 53. This in turn allows the bar 15 to rise on the pin guides 16-16 under action of the springs 14-14, causing the various resilient contact elements 17 that have been deflected to one side of the rods 20, to rise with the said bars 15 and operatively engage the said sides of the said rods. Consequently upon the release of the levers 22 the various contact elements 17 are retained by the insulated rods 20 against the conductors 19. The levers 22 not selected by the magnets 38, however, are not moved by the bar 26, and retain their normal contact position against the conductors 18. 20 The deflation of the bellows of the unit 106, effected through the release of push button 117, causes the panel 92 through the medium of the connecting rod 103 and associated switch lever 91, to pivot on the shaft 25 90 and return the various spring contact elements 99 and 100 into contacting engagement with their corresponding contact plates 101 and 102 on the base panel 88. This closes the return circuits between the conductors 18 and 19 in the combination box 8 and the respective combination keys or switches 3 on the organ console.

The deflation of the bellows 114b of the pneumatic unit 105 results in the said bellows through the action of the spring 115 and connecting rod 34 to return the bar 26, and consequently the levers engaged in the notches 32 thereof, to its normal position.

40 Thus, the first combination is set and likewise each succeeding combination in the manner described, until all have been set, each setting employing a separate combination button 117 in conjunction with the master button 116.

The organist having completed the combination settings is now ready to play the musical selections.

However, before the actual playing 50 thereof, a switch diagrammatically illustrated at 135 and shown mounted on the panel 6 adjacent the push buttons 117 in Figure 7, is actuated closing through the leads 136 and 137, the circuit from the line 130 to the electro-magnetic valve 111 of the auxiliary pneumatic unit 108.

Also before playing, the combination keys or switches must be reset to correspond to the first combination of the same used in the 60 music. This is accomplished by the organist depressing the first push button 117 of the group shown, the said button corresponding to and controlling the first combination selection previously set in the combination box.

The depression of the said push button 117 results as before in the connection of the leads 124 and 130 with the trunk conductor 122, thereby energizing the electro-magnetic valves 111 of the pneumatic units 106 and 107 respectively and causing the bellows of said units to expand in the manner heretofore described.

Through the lead 136 and 137, connected to lead 130, the electro-magnetic valve 111 of the unit 108 is also energized resulting in a like expansion of the bellows of the respective unit, causing the expanding wing thereof to be brought into the line of operative engagement with, and intercepting the expandible wing of the bellows of the unit 107 through abutment 138 mounted thereon.

This limits the downward travel of the lever 49, the said lever 49 having been magnetized by the magnet 62 and brought into engagement with the bracket 57 in its respective downward travel upon the depression of the said button 117.

This permits the crank portions 46 of the levers 43 to bear in contact relation only against the various contact elements 17, being held from further movement by the engagement of the abutment 138 by the bellows of the unit 108.

A lead wire 139 connecting to the trunk conductor 122 energizes at all times the spring contact strips 65 through the conductor 64, and upon the contacting of lever 43 against the side thereof all of the contact elements 17 are energized, the said lever 43 and the elements 17 in turn energize the respective conductors 18 or 19 according to which one they are in contact with.

Thusly the various current impulses are sent through the leads 140 and 141 to the respective terminals 97 and 98 on the transfer switch 87. Then through the spring contact elements 99 and 100 and opposed plates 101 and 102 the circuits are completed to the combination switch 3, energizing either the magnet 81 or 82 thereof according to the setting of the elements 17 in the combination box. This operates the said switch 3 to either an "on" or "off" position thereby making the first combination.

As these actions take place simultaneously and due to the flexibility of the contact elements 95, 99 and 100 the return circuits are completed through the switch 87 before the said switch has moved sufficiently to break the circuit between the said contact elements 99 and 100 and their respective contacting plates 101 and 102.

As the foregoing description has fully described the method and means whereby a combination of combination keys or switches may be first selected, then the said selection "set" in the combination box, and thereafter through a control switch or button be caused to be brought into working rela-

tion with the organ at the option of the organist by the depression of the said button, it will be obvious that any number of combinations may be made and controlled 5 in the same manner. Also by operating the control buttons successively, by the finger tips the combinations may be successively changed throughout the rendition of any musical selection and without any perceptible pause in the playing.

The invention having been set forth, what is claimed is:

1. Stop selector actuating mechanism for organs comprising stop actuators manually movable to select a desired stop combination, "on" and "off" circuits for each actuator including respectively means to move the actuator to "on" and "off" positions, a plurality of banks of switches each bank of 15 switches containing a switch for each actuator, each switch controlling the "on" and "off" circuits of the associated actuator to open and close the same, and normally closing the "off" circuit, a plurality of means 20 each cooperating with the switches of each bank common to a given actuator and operable only after a manual setting of the actuators and a preliminary movement of a switch bank for moving the switches of 25 selected actuators in such bank to open the "off" and close the "on" circuit thereof, and means for selecting the bank of switches to be operated by the operation of the last named means.
- 35 2. A mechanism of the character described, a plurality of switches each including an element alternately engageable with a pair of contacts and normally engaged with one thereof, a member associated with each switch and adapted when operated to move the switch out of engagement with said contact and into engagement with the other contacts, a longitudinal movable bar and electro-magnet for relatively connecting 40 said members with the bar to be operated thereby.
- 45 3. A device as set forth in claim 2 wherein in each switch is movable out of engagement with its normally engaged contacts only after a preparatory operation thereof, and means for simultaneously moving all the switches to effect such preparatory movement.
- 50 4. Stop-selector-actuating mechanism for organs comprising stop actuators manually movable to select a desired stop combination, electrical operating means for selectively moving said actuators to "on" and "off" positions, circuits for said operating means, a plurality of banks of switches, each bank containing a switch for each operating means, said switch being normally positioned to actuate the operating means and place the actuator in "off" position, means 55 for moving said switches to the "on" position comprising a member for each actuator and common to the switches associated with said actuator in all of said banks, means for preventing operation of the switch-moving means until the associated bank has been bodily moved, means for bodily moving a selected bank, and means for connecting the selected switch-operating means to a movable member to be actuated thereby.
- 60 5. Stop-selector-actuating mechanism for organs comprising stop actuators manually movable to select a desired stop combination, electrical operating means for selectively moving said actuators to "on" and "off" positions, circuits for said operating means, a plurality of banks of switches, each bank containing a switch for each operating means, said switch being normally positioned to actuate the operating means and place the actuator in "off" position, means 65 for moving said switches to the "on" position comprising a member for each actuator and common to the switches associated with said actuator in all of said banks, means for preventing operation of the switch-moving means until the associated bank has been bodily moved, means for bodily moving a selected bank, and means for connecting the selected switch-operating means to a movable member to be actuated thereby.

tion comprising a member for each actuator and common to the switches associated with said actuator in all of said banks, means for preventing operation of the switch-moving means until the associated bank has been 70 bodily moved, means for bodily moving a selected bank, and means for connecting the selected switch-operating means to a movable member to be actuated thereby.

5. Stop-selector-actuating mechanism for 75 organs comprising stop actuators manually movable to select a desired stop combination, electrical operating means for selectively moving said actuators to "on" and "off" positions, circuits for said operating 80 means, a plurality of banks of switches, each bank containing a switch for each operating means, said switch being normally positioned to actuate the operating means and place the actuator in "off" position, means for moving said switches to the "on" position comprising a member for each actuator and common to the switches associated with said actuator in all of said banks, means for preventing operation of the switch-moving 85 means until the associated bank has been bodily moved, means for bodily moving a selected bank, and means for connecting the selected switch-operating means to a movable member to be actuated thereby, said 90 switches each comprising a flexible element with which the operator directly engages to shift the flexible element and establish the "on" circuit, the means for preventing operation of the switches comprising stops with 95 which said flexible elements engage until the associated bank has been shifted through a predetermined distance.

6. Stop-selector-actuating mechanism for 100 organs comprising stop actuators manually 105 movable to select a desired stop combination, electrical operating means for selectively moving said actuators to "on" and "off" positions, circuits for said operating means, a plurality of banks of switches, each bank containing a switch for each operating means, said switch being normally positioned to actuate the operating means and place the actuator in "off" position, means for moving said switches to the "on" position comprising a member for each actuator and common to the switches associated with said actuator in all of said banks, means for preventing operation of the switch-moving 110 means until the associated bank has been bodily moved, means for bodily moving a selected bank, and means for connecting the selected switch-operating means to a movable member to be actuated thereby, and a common means for shifting 115 a selected bank and for supplying current to the switches of the bank.

7. Stop-selector-actuating mechanism for 120 organs comprising stop actuators manually movable to select a desired stop combina- 125

tion, electrical operating means for selectively moving said actuators to "on" and "off" positions, circuits for said operating means, a plurality of banks of switches, each bank containing a switch for each operating means, said switch being normally positioned to actuate the operating means and place the actuator in "off" position, means for moving said switches to the "on" position comprising a member for each actuator and common to the switches associated with said actuator in all of said banks, means for preventing operation of the switch-moving means until the associated bank has been bodily moved, means for bodily moving a selected bank, means for connecting the selected switch-operating means to a movable member to be actuated thereby, and a common means for shifting a selected bank and for supplying current to the switches of the bank, and means for controlling operation of the last-named means to determine in which of its capacities it is effective.

In testimony whereof I affix my signature.

CHRISTOPHER CHARLES DARGIS.
